W. C. DILLON,
AUXILIARY AIR DEVICE,
APPLICATION FILED SEPT. 14, 1920.

1,392,922.

Patented Oct. 11, 1921.

UNITED STATES PATENT OFFICE.

WILLIAM C. DILLON, OF FORT DODGE, IOWA.

AUXILIARY-AIR DEVICE.

1,392,922.

Specification of Letters Patent. Patented Oct. 11, 1921.

Application filed September 14, 1920. Serial No. 410,261.

To all whom it may concern:

Be it known that I, WILLIAM C. DILLON, a citizen of the United States, and a resident of Fort Dodge, in the county of Webster 5 and State of Iowa, have invented a certain new and useful Auxiliary-Air Device, of which the following is a specification.

The purpose of my invention is to provide an auxiliary air device of very simple, durable and inexpensive construction, which can be easily adapted to an internal combustion engine, between the carburetor and the intake manifold for supplying auxiliary air to the fuel mixture.

10 A further object is to provide such a device, which is automatic in its ordinary operation and which may be controlled from the dash or other point at a distance from the device.

20 A further object is to provide such a device, having air screening means and novel means for supporting the air screening.

Still a further object is to provide such a device, which can be assembled as a unit for 25 packing or transportation, and also for installation on the engine.

With these and other objects in view, my invention consists in the construction, arrangement and combination of the various 30 parts of my device, whereby the objects contemplated are attained, as hereinafter more fully set forth, pointed out in my claims and illustrated in the accompanying drawings, in which:

35 Figure 1 shows a side elevation of an intake manifold and carburetor and connecting pipe equipped with an auxiliary air device, embodying my invention.

Fig. 2 shows a detail, sectional view taken 40 on the line 2—2 of Fig. 1; and

Fig. 3 shows a detail sectional view taken on the line 3—3 of Fig. 2.

In the accompanying drawings, I have used the reference numeral 10 to indicate 45 generally a carburetor, which communicates with the pipe 11, leading to an intake manifold 12.

In the form of the device shown herein, the carburetor is provided with a flange 13, 50 which is arranged where my device is not used to abut against a flange 14 on the pipe 11, these flanges being secured together by bolts or the like.

My device is designed to be placed between 55 the flanges 13 and 14 and comprises

a casting or other piece preferably of metal, having substantially the shape of a thin plate 15, provided with a central opening 16 arranged to register with the openings in the carburetor and the pipe 11. 60

The plate 15 has holes 17 to receive the bolts 18, whereby the plate is fastened to the flanges 13 and 14. Gaskets 19 are preferably placed on each side of the plate.

Extending downwardly from the plate 65 15 near the ends thereof are vertically arranged posts 20, the lower ends of which are screw-threaded, as at 22 to receive nuts 23.

Extending downwardly from the central 70 portion of the plate 15 is an extension 24, which has at its lower end a laterally extending lug 25. On the opposite sides of the extension 24 are downwardly extending members 26, which are externally screw-threaded. Holes 27 extend vertically through the extensions 26 and the body of the plate 15 from the outer ends of the extensions 26 to the opening 16, as illustrated for instance in Fig. 2. 80

Mounted on the lower ends of the extensions 26 are cylindrical caps 28, each having at its upper portion a screw-threaded bore 29 adapted to receive one of the extensions 26. 85

At the bottom of the hole or bore 29 is a shoulder 30, below which is a reduced bore 31. A small inlet hole 32 extends from the lower end of the bore 31 to the exterior of the cap 28. 90

Mounted in the holes 27 and projecting well into the holes 16 are air screening devices 33, preferably made of a roll of meshed wire. The shoulder formed at the lower end of each bore 31 forms a valve 95 seat, which coacts with a ball valve 34.

Slidably mounted on the members 20 is a cross bar 35 on which is a felt or leather member 36. Extending through the cross bar 35 is a hole 37, through which extends 100 a fastening device, such for instance as a cotter pin 38. In the laterally extending portion 25 of the member 24 is an inclined hole 39, through which the cotter pin 38 or the rope or the like 40, to which it is secured may be slidably extended. The cable or rope 40 is designed to be extended through the dash of an automobile or the like, so that by pulling on the rope, the bar 35 may be drawn upwardly for bringing 110

the member 36 against the lower end of the caps 28 for closing the openings or passages 32.

5 Springs 41 mounted on the members 20 yieldingly hold the bar 36 at the downwardly limit of its movement.

In the practical use of my improved auxiliary air device, the driver of the car, when starting the car, pulls on the rope 40 for 10 closing the passages 32 and preventing the ingress of any air to the pipe 11.

15 After the engine has been warmed up, the rope 40 is released, whereupon the springs 41 will force the bar 35 away from the caps 30, and the suction from the engine will draw air through the passages 32, 31 and 27 and through the screening or filtering members 33 into the mixture in the pipe 11.

It will, of course, be obvious that when a 20 vacuum is created in the pipe 11, the outer air will force its way past the balls 34, and the greater the vacuum, the greater will be the amount of auxiliary air supplied to the engine.

25 It will be seen that the bar 35 may be adjusted close to or far from the caps 28, and that by holding the bar close to the caps 28, but not in tight engagement therewith, the volume of auxiliary air admitted 30 to the intake manifold may be reduced and regulated.

The auxiliary air device may be made inoperative for starting or in cold weather, where it is desirable not to admit any auxiliary air to the fuel mixture.

35 It will be noted that my device is of extremely simple and inexpensive construction. It occupies small space and can therefore be cheaply stored or transported.

40 It may be mentioned that the lower ends of the members 33 are flared slightly, so as to be engaged between the lower ends of the members 26 and the shoulders 30 for thereby locking the screening or filtering 45 members 33 against movement. I have found this is desirable for otherwise, these members 33 will sometimes be jerked inwardly and will then drop back, thereby pounding their ends and compressing them, 50 so as to make almost a closed end, which reduces the air inflow.

Furthermore by fastening the ends of the members 33, there is no danger of their being drawn into the intake manifold.

55 I find that the best results are obtained when the caps 28 are vertically arranged. The valves work more satisfactorily than is otherwise the case. The members 20 serve as guides as well as supports for the bar 35.

60 The holes 32 are of different sizes so that at the lower speeds only one valve operates, while at higher speeds both valves operate.

Some changes may be made in the construction and arrangement of my improved 65 auxiliary air device without departing from

the essential purpose and spirit of my invention, and it is my intention to cover by my claims, any modified forms of structure or use of mechanical equivalents, which may be reasonably included within their scope. 70

I claim as my invention:

1. An auxiliary air device, comprising a plate designed to be interposed in the path of travel of the fuel mixture of an internal combustion engine, said plate having an 75 opening, an extension on said plate, an opening extended through said extension and the body of the plate to said first opening, a cap mounted on said extension, a filtering device mounted in said last opening, said cap having an opening extending through it and a portion forming a valve seat, a ball valve for coacting with said seat, means for closing the passage at the outer end of the cap, said means comprising a bar slidably 80 mounted on said plate.

2. An auxiliary air device, comprising a plate designed to be interposed in the path of travel of the fuel mixture of an internal combustion engine, said plate having an 85 opening, an extension on said plate, an opening extended through said extension and the body of the plate to said first opening, a cap mounted on said extension, a filtering device mounted in said last opening, said cap having an opening extending through it and a portion forming a valve seat, a ball valve for coacting with said seat, means for closing the passage at the outer end of the cap, said means comprising a bar slidably 90 mounted on said plate, a lateral extension on said plate, having an inclined hole and a member connected with said bar and extended through said hole for actuating said bar. 95

3. An auxiliary air device, comprising a plate designed to be interposed in the path of travel of the fuel mixture of an internal combustion engine, said plate having an opening, an extension on said plate, on opening extended through said extension and the body of the plate to the first opening, a cap mounted on said extension, a filtering device mounted in said last opening, said cap having an opening extending through it and a portion 100 forming a valve seat, a ball valve for coacting with said seat, means for closing the passage at the outer end of the cap, said means comprising a bar slidably mounted on said plate, a lateral extension on said 105 plate, having an inclined hole and a member connected with said bar and extended through said hole for actuating said bar, and means for yieldingly holding said bar 110 away from said cap. 115

4. In a device of the class described, a plate adapted to be interposed in the path of travel of the fuel mixture of an internal combustion engine, having a hole, downward extensions on said plate, openings ex- 120 125 130

- tending through said extensions and through the body of the plate to said first opening, caps mounted on said extensions, having passages through them, ball valves for controlling the passage of air through said last passages, and means for closing the outer ends of said last passages.
5. In a device of the class described, a plate adapted to be interposed in the path of travel of the fuel mixture of an internal combustion engine, having a hole, downward extensions on said plate, openings extending through said extensions and through the body of the plate to said first opening; 10 caps mounted on said extensions, having passages through them, ball valves for controlling the passage of air through said last passages, and means for closing the outer ends of said last passages, and means for 15 closing the outer ends of said last passages, said means comprising a plate, means for yieldingly holding said plate away from said caps, and means for moving said plate to position adjacent to said caps.
- 20 6. In a device of the class described, a plate adapted to be interposed in the path of travel of the fuel mixture of an internal combustion engine, having a hole, downward extensions on said plate, openings ex- 25 tended through said extensions and through the body of the plate to said first opening, caps mounted on said extensions having passages through them, ball valves for controlling the passage of air through said last passages, means for closing the outer ends of said last passages, said means comprising a bar, members on said plate for slidably supporting said bar, yielding devices for moving said bar away from said caps, and means for drawing said bar 30 against said caps.
7. In a device of the class described, a plate adapted to be interposed in the path of travel of the fuel mixture of an internal combustion engine, having an opening therethrough, an extension on said plate, the body of said plate having an opening extending from the outer end of the extension to said hole, a filtering device mounted in said last opening, a cap mounted on said extension 40 having a shoulder on its interior and provided with a passage extending through it, one end of said filtering device being engaged by the said shoulder and said extension, a valve for controlling the passage 45 through said cap, and a member for closing said passage.
- 50 Des Moines, Iowa, August 28, 1920.
